UNITED STATES PATENT OFFICE

2,627,863

DISHWASHER AND ARTICLE INTERCEPTING
DRAWER THEREFOR

Marie Cavigchioli, New York, N. Y.

Application June 7, 1947, Serial No. 753,255

5 Claims. (Cl. 134—104)

1

This invention relates to a dish washer and article intercepting drawer therefor and, more particularly, it relates to a corner dish washer containing a removable refuse catching tray.

In my United States Patent #2,353,993, issued July 18, 1944, and my co-pending application S. N. 739,705, filed April 5, 1947, now Patent No. 2,573,128, dated October 30, 1951, I have described dish washing units containing traps for selectively catching waste material and cutlery. Said traps are easily removable from the units and do not interfere with the units while in operation.

An object of the present invention is to provide unique improvements over those indicated in the hereinabove noted constructions.

Another object of this invention is to permit the flow of wash and drain water in a dish and cutlery washing unit while preventing the loss of small objects which are being washed and drained.

One other object of the present invention is to provide an easily constructed, drawer trap adapted to catch small objects and direct the flow of wash fluid from the trap.

A further object of this invention is to provide a withdrawable trap unit for a dish and like washing machine, said unit having a drawer, drip means and perforated catching means.

A more specific object of this invention is to provide a drawer unit whose structure is such that it contacts all the walls of the unit in which it is inserted.

Further objects and advantages of the present invention will become apparent from the following description taken in connection with the accompanying drawings in which:

Fig. 1 is a horizontal, sectional view of a preferred embodiment of my invention taken on line 1—1 of Fig. 2;

Fig. 2 is a perspective view of a dish washing machine containing my invention;

Fig. 3 is a plan view of a corner drawer for use in a dish washing unit;

Fig. 4 is a sectional view taken on line 4—4 of Fig. 3 of a corner drawer as retained in the dish washing unit; and

Fig. 5 is a perspective view of the drawer frame shown in Fig. 4 with front exterior part removed.

Referring now to the drawings in which like reference characters denote like parts throughout, there is provided a dish and cutlery washing unit 10 of the ordinary type, as shown in Fig. 2, and which is used in the kitchens of restaurants, homes and the like. Said unit contains a plural-

2

ity of spaced vertical supporting legs, 11, 12, 13 and 14, respectively, on which is mounted a lower platform 15 supporting a motor and pump unit 16 in communication with a water basin section 17 as shown more clearly in Fig. 1.

Said basin or water chamber section 17 is provided with the usual type of hot and cold water connections, 18 and 19, respectively and which are characteristic of dish washing machines, a drain and overflow line 20 with controlling valve, and a rinse valve 21, as shown in Fig. 2. The water contained in said chamber 17 is heated by any suitable means, such as a gas unit 22, disposed beneath said water chamber 17.

Disposed above water chamber 17 is a plurality of horizontal perforated pipes 26 in connection with motor and pump unit 16. Above said pipes 26 is an open platform or bracket 27 on which are placed wire trays of dishes, cutlery and other washable items used in restaurants, kitchens and the like.

Provided above said bracket 27 is spray chamber 25 consisting of walls 28, 29, 30 and 31, respectively, which are extensions of the middle portion forming the water chamber 17. Two of said walls 28 and 31 comprise vertical moving partitions for permitting the insertion and removal of trays containing dishware, cutlery, etc. Said partitions 28 and 31 may be of glass to permit observation of the cutlery and dishware during the washing operation.

It will be noted that, disposed above the water chamber 17, there is provided a sloped flooring 23 having an opening 24 to permit the return of water into water chamber 17 from spray chamber 25.

Beneath said floor 23 and the spray pipes 26, there is provided a drawer 32 preferably of a polygonal shape, as shown in Figs. 1, 3, 4 and 5. Said drawer 32, because of its form, extends through the diagonal or major length of the spray chamber 25 so as to facilitate the catching of all waste material and also of any small objects which may tend to become loose from the trays and escape towards the water chamber. Said drawer 32 comprises an integral, hexagonal shaped frame 33 containing long side members 34 and 35, respectively, and opposed diagonally disposed short members 36, 37, 38 and 39, respectively, all of which, for purposes of illustration, are of right angle construction. Said short members 36 and 37 fit flush against the walls 29 and 30 of the water chamber while long arm members 34 and 35 are adapted to slide on rails 40 and 41 set in the

compartment intermediate the spray chamber 25 and water chamber 17. Short members 38 and 39 are provided with attached extending flange members 42 and 43, respectively, which act as a stop against the walls 28 and 31 of the water chamber 17 when the drawer is inserted into the intermediate chamber 44. It will be noted that said latter members 42-43 are provided with a handle 45 as shown in Fig. 3 to permit the withdrawal of said drawer 32. Said drawer has a depending portion 45' as shown in Fig. 4. It is furthermore provided with a drip tray member 46 hinged at its forward end portion 47 to the drawer 32, as shown in Figs. 1, 3 and 4, and has an upwardly flanged portion 46' adapted to fit snugly against depending flange 45'.

Tray 46, it will be noted, extends the major portion of the drawer frame 32 and is adapted to drop downwardly, as shown in Figs. 4 and 5, to permit the flow of water from pipes 26 through the opening 24 and into water chamber 17. Said drawer 32 is provided with a pair of removable, perforated baskets, 48 and 49, each of which corresponds to one-half the length of the drawer frame as shown in Fig. 3. It is to be noted that, in lieu of having perforated baskets, as shown, a single complete basket may be used having substantially the same shape as that of the drawer frame.

The downwardly extending portions of walls 28 and 31 forming part of the intermediate chamber 44 and washing chamber 17 are provided with a drip gutter 50 disposed beneath the external or flanged portion of the drawer 32, as shown in Fig. 2. Said gutter 50 is adapted to collect any moisture that may seep from the drawer frame and permit return of the water into the water chamber through the openings 51 in said walls of the water chamber.

It will be noted from the description and accompanying drawings, that, during the spraying, washing and rinsing operations of dishes, cutlery and the like, wash water passes to flooring 23 into opening 24 and down through baskets 48 and 49 on drawer 32 in intermediate chamber 44. Any leaking water from the front of drawer 32 collects and is guided by said drip tray gutter 50 through openings 51 into the water chamber 17. Any solid items that may escape from the dish trays will be collected on the perforated baskets and are easily recovered.

To remove cutlery or similar objects collected in baskets 48 and 49, said drawer 32 may be easily removed from the intermediate chamber by raising handle 45 until the forward, upper portion of the frame 33, as shown in Fig. 4, reaches its limit of upward movement. The handle 45 is raised in order to lift the lower front corner of tray 46 above the level of the lower edge of the opening through the corner of chamber 10. The drawer is then pulled outwardly of the chamber so as to permit the hinged drip tray 46 to slide along the flanged rails 40 and 41.

Furthermore, by my invention, small objects are readily and easily recovered during washing operations. Also, any waste or refuse material is trapped and, by continuous washing, is broken down into small particles which are easily washed off.

While a preferred embodiment of my invention 70 has been described and shown herein, it is to be understood that various modifications as to form,

use and arrangement of parts may be made without departing from the spirit and scope of the invention as claimed herein.

I claim:

5 1. The combination with a dish and like washing machine having a spray chamber, the improvement comprising a polygonal shaped catch drawer diagonally insertible into said machine and disposed below the spray chamber of said 10 machine, a normally downwardly tiltable tray forming the floor of the drawer adapted to move relatively of said drawer, and a perforated member fitting into the drawer adapted to hold cutlery therein that may have been washed down from 15 the spray chamber during the use of said machine.

2. A drawer for use in dish and like washing machines comprising a frame, a floor hinged to one end of said frame forming a tray therewith normally adapted to extend downwardly in said machine, perforated means in the drawer adapted to catch objects coming into contact therewith, while permitting the flow of wash water therethrough, and means on said frame for manipulating said frame to remove same from the machine and also raise the floor as the frame of the same is being withdrawn from the machine.

3. In combination with a receptacle, a drawer comprising a frame adapted to fit into the receptacle, a floor member hinged at one end to the frame to permit dipping of said floor member, flange means extending upwardly of said end of the frame to prevent leakage from said end, means attached to the flange means to permit withdrawal of the drawer from the receptacle, and a basket conforming to the shape of the drawer and adapted to fit in said drawer.

4. In combination with a receptacle in a dish and like washing machine, a drawer comprising a hexagonal frame adapted to fit diagonally into said receptacle, a floor pivoted at one end of said frame adapted to slope downwardly in the receptacle, perforated means in the frame adapted to catch objects coming into contact therewith while permitting the flow of wash water therethrough and externally disposed means on said frame for removing the frame from the washing machine, said pivoted floor being automatically lifted when the drawer is pulled out of the receptacle to provide a bottom for said drawer.

5. A drawer according to claim 4, in which the free end of said floor is down-turned to prevent inadvertent withdrawal of the drawer beyond a point where removal of the perforated means is possible.

MARIO CAVICCHIOLI.
